UNITED STATES PATENT OFFICE.

HENRY C. GILL, OF MADISON, OHIO.

CROWN-TERRET FOR HARNESS.

SPECIFICATION forming part of Letters Patent No. 279,149, dated June 12, 1883.

Application filed March 26, 1883. (No model.)

To all whom it may concern:

Be it known that I, HENRY C. GILL, a citizen of the United States, residing at Madison, in the county of Lake and State of Ohio, have 5 invented certain new and useful Improvements in Harness Crown-Terrets, of which the following is a specification, reference being had therein to the accompanying drawings.

This invention has relation to crown-terrets; 10 and it consists in so constructing and arranging the parts as to produce an improved article of manufacture, as will be hereinafter fully described, and pointed out in the claim appended.

Referring by letter to the accompanying 15 drawings, Figure 1 represents a front view, and Fig. 2 a vertical sectional view, of the terret.

A designates the terret, the upper portion of which consists of an annular frame, in which a plate, *a*, is pivoted to swing through the 20 opening in said annular frame. This annular frame is supported on a shank, *b*, cast therewith, and below this shank *b*, and cast therewith, is a rectangular guide frame or base, having a rectangular opening, *c*, for the stay-billets, overcheck-rein, or both, as may be desired. 25 The under side of the guide-frame is provided with the threaded portion *d* for the reception

of a nut that secures the crown-terret to the headstall. By this construction the rein or billet opening or space is brought close to the 30 headstall and the strain upon the terret is greatly lessened. A terret provided with a rectangular space near its upper end and a circular space near a convex base, from which a threaded shank projects downwardly, has 35 been used for round or flat reins, and such a device I do not claim.

Having thus fully described my invention, what I claim, and desire to secure by Letters Patent, is—

As an improved article of manufacture, a crown-terret having the usual annular portion, *A*, and swinging plate *a*, and provided on its stem *b* with the slotted rectangular base *c*, to receive the reins, and having the threaded portion *d* of the stem immediately below said base, 45 as shown and described.

In testimony whereof I affix my signature in presence of two witnesses.

HENRY C. GILL.
